UNITED STATES PATENT OFFICE.

LEONARD LOOP, OF OKMULGEE, OKLAHOMA.

DEEP-WELL PUMP.

1,163,024.

Specification of Letters Patent. Patented Dec. 7, 1915.

Application filed October 16, 1914. Serial No. 867,000.

To all whom it may concern:

Be it known that I, LEONARD LOOP, a citizen of the United States, residing at Okmulgee, in the county of Okmulgee and State of Oklahoma, have invented a new and useful Deep-Well Pump, of which the following is a specification.

The present invention appertains to pumps for extracting oil and other liquids from deep or Artesian wells.

One of the objects of the present invention is to provide a novel valve for a deep well pump, which is designed for preventing the particles of sand and other foreign matter within the well tubing or casing from settling or precipitating back or downwardly to the piston and check valve, especially when the pump is idle, and to thereby prevent the piston from becoming clogged or stuck within the pump barrel, and to also prevent the barrel and piston from being scratched and worn due to the presence of sand and other extraneous matter.

Another object of the invention, is to provide in combination with the sand valve, of novel means for driving the same home within the pump, and whereby the piston may be actuated for driving the check valve home as usual.

It is also within the scope of the invention, to provide a sand valve structure and driving means therefor which will be comparatively simple and inexpensive in construction, which may be readily assembled with the prevailing types of deep well pumps, and which will be thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in its preferred embodiment in the accompanying drawings, wherein:

Figure 1 is a vertical central section through the pump structure, illustrating the present improvements applied thereto.

Figs. 2 and 3 are enlarged cross sections taken on the lines 2-2 and 3-3, respectively, of Fig. 1.

In the drawing there is illustrated an ordinary pump barrel 1 which is connected by means of the coupling or union 2 to the lower end of the well tubing or casing 3, a common check valve 4 being disposed within the lower end of the barrel 1 and being adapted to be driven into the coupling or nipple 5 threaded upon the lower end of the barrel. The usual piston 6 is slideable within the barrel 1 and is provided with a valve for enabling the oil or other liquid to pass upwardly through the piston when the piston is depressed. The piston 6 is provided with an upwardly projecting piston rod 7 extending through the coupling or union 2 into the lower portion of the well tubing 3.

In carrying out the present invention, the upper end of the pump barrel 1 is tapered, as at 8, to receive the lower tapered end of an annular valve seat 9 mounted upon the piston rod 7 within the coupling 2. The annular valve seat 9 is provided with an annular series of vertical bores or passages 10 therethrough.

The valve seat 9 is provided with an upstanding neck 11 surrounding the piston rod 7 and provided at its upper end with a head 12 having an upstanding tongue 13 of arcuate cross section and fitting against one side of the piston rod 7.

The head or coupling member 14 is threaded upon the upper end of the piston rod 7, and is provided with an upstanding threaded stub 15 for the engagement of the usual pump rod 16 which extends upwardly through the well tubing 3 to the actuating mechanism (not shown). The head 14 is provided with a depending tongue 17 of arcuate cross section and snugly fitting one side of the piston rod 7 to complement the tongue 13.

An annular valve 18 is mounted slidably upon the neck 11 between the valve seat 9 and the head 12, and is normally seatable upon the seat 9 over the passages 10, to serve as a check valve for supporting the column or head of oil or other liquid within the well tubing 3.

In the ordinary operation of the pump,

the pump rod 16 is normally lifted sufficiently to raise the head 14 and its tongue 17 above the tongue 13 so as not to interfere therewith when the pump rod is reciprocated to actuate the piston rod and piston carried thereby for the usual pumping operation.

The cardinal feature of the invention resides in the fact that when the oil or other liquid is forced upwardly by the piston, the oil will be forced through the passages 10 of the valve seat 9, to raise the valve 18, and when the piston moves downwardly or is idle, the valve 18 will be seated, to not only support the column of liquid within the well tubing, but also to prevent the settling or precipitation of sand or other foreign matter from within the well tubing down into the pump barrel 1, which not infrequently results in the clogging or sticking of the piston, or the scratching or marring of the piston and pump barrel. Considerable trouble is experienced in practice, especially after the the pump has been idle for a period of time, in the accumulation of sand within the pump barrel, due to the fact that the sand will precipitate downwardly to the piston. With the present sand valve structure, however, these objections are eliminated. In this connection it is to be understood that the oil which is pumped by the deep well pumps is usually extracted from sand rock or similar strata, which results in particles of sand or other foreign matter being drawn or sucked into the pump barrel and tubing, which in precipitating is injurious to the leather cups or packings of the piston and check valve.

The present appliance also embodies means for driving the sand valve seat 9 home, and for enabling the check valve 4 to be driven home in the usual manner. Thus, when the pump rod 16 is lowered and swung properly to enable the tongue 17 to overlap the tongue 13, as seen in Fig. 1, the pump rod may be reciprocated for causing the piston 6 to impinge against the check valve structure 4 to drive the check valve structure tightly into place so that it will not be dislodged during the operation of the pump. When the pump rod is lowered to the limit, the interengageable means of the piston and check valve structure 4 are arranged to be interlocked by a turning movement of the pump rod 16 in the usual manner, and the tongues 17 and 13 being overlapped will cause the piston rod 7 to turn with the pump rod, and at the same time, the valve seat 9 will be turned with the tongue 13 and its head 12. After the check valve 4 has been driven home, the valve seat 9 may be driven tightly into place within the tapered portion 8 of the well barrel 1, and to this end, the pump rod 16 is lifted sufficiently and then turned to enable the tongue 17 to

impinge or seat upon the upper end of the tongue 13, which will enable the valve seat 9 to be forced downwardly. Thus, by reciprocating the pump rod 16, the tongue 17 may be forcibly struck against the tongue 13 carried by the valve seat 9 to drive the valve seat into place. Then, by further raising the pump rod, the pumping operation may take place without interference. In removing the parts from the barrel, the piston 6 may be lowered to catch onto the check valve structure 4, and then by raising the piston, it will lift the sand valve structure therewith, as will be apparent.

Having thus described the invention, what is claimed as new is:—

1. In a well pump, a barrel, an annular valve seat fitted therein and having an annular series of passages, a piston working within the valve and having an upwardly projecting piston rod passing through the valve seat, an annular valve disposed above and seatable upon the valve seat over the said passages, an upwardly projecting tongue carried by the valve seat, and a member carried by the piston rod and arranged to either impinge or to move below the upper end of the tongue when the piston rod is turned to predetermined positions.

2. In a deep well pump, a barrel, an annular valve seat seated therein and having an annular series of passages and an upstanding neck, a piston within the barrel having an upstanding piston rod passing through the valve seat, the said neck having an upstanding tongue adjacent one side of the piston rod, an annular valve slidable upon the said neck and seatable over the said passages, and a member carried by the piston rod and seatable upon or movable below the upper end of the said tongue when the piston rod is turned to predetermined positions.

3. In a deep well pump, a barrel an annular valve seat fitted therein and having an annular series of passages, a piston within the valve and having an upstanding piston rod passing through the valve seat, an upstanding tongue carried by the valve seat adjacent one side of the piston rod, an annular valve disposed above and seatable upon the valve seat over the said passages, a member engaged upon the piston rod and having a downwardly projecting tongue adapted to either seat upon or overlap the aforesaid tongue.

4. In a deep well pump, a valve, an annular valve seat fitted therein and having an annular series of passages and an upstanding neck, a piston within the valve having an upwardly projecting piston rod passing through the valve seat, the said neck having a head provided with an upstanding tongue of arcuate cross section fitting against one side of the piston rod, an annular valve

slidable upon the said neck and seatable over the said passages, and a member secured upon the piston rod and having a depending tongue of arcuate cross section fitting against one side of the piston rod and arranged to seat upon or overlap the aforesaid tongue.

In testimony that I claim the foregoing as my own, I have hereto affixed my signature in the presence of two witnesses.

LEONARD LOOP.
